CLAIM

The ornamental design for a combined pillow, cassette player and speakers, as shown and described.

DESCRIPTION

FIG. 1 is a perspective view of a combined pillow, cassette player and speakers showing my new design; FIG. 2 is a left side elevational view thereof, the right side being a mirror image and the partial broken-line depiction of the head being for illustrative purposes only and forming no part of the claimed design; FIG. 3 is a front elevational view thereof; FIG. 4 is a rear elevational view thereof; and FIG. 5 is a bottom plan view thereof. The cord element is shown broken-away in the views to indicated indeterminate length.
